Attorney,

UNITED STATES PATENT OFFICE.

THEODOR JOHANN CAVIER, OF BREMEN, GERMANY, ASSIGNOR TO MASCHINENFABRIK BREMEN, G. M. B. H., OF BREMEN, GERMANY.

SHOE-SOLE PROTECTOR.

1,177,484.

Specification of Letters Patent. Patented Mar. 28, 1916.

Application filed August 21, 1913, Serial No. 785,942. Renewed November 27, 1915. Serial No. 63,908.

To all whom it may concern:

Be it known that I, THEODOR JOHANN CAVIER, a subject of the Emperor of Germany, and resident of 170 Geschworenenweg, Bremen, Germany, have invented new and useful Improvements in Shoe-Sole Protectors, of which the following is a specification.

Ordinarily, the attachment of a protector to a shoe-sole is effected by flexible nails, which are beveled, curved or rounded at their ends and which, owing to the resistance they meet, when driven into the sole, are bent down sidewise in the latter. Consequently, the fastening is not always reliable, since the resistance offered by the sole is variable, being sometimes greater and sometimes less than required. When it is excessive, as in the case of hard and dry soles, the thin, flexible nails readily become bent, in which instance, the attachment of the protector to the sole is not effected. When, on the other hand, the resistance is too slight, as is the case with thin, worn, or perforated soles, and, also, with soles softened by moisture, or if the sole offers no resistance whatever, the nails enter the sole without bending, and a spiking action only is effected.

The present invention aims to avoid these drawbacks by proposing an improved protector comprising a gable-shaped plate, which, when struck upon its ridge line, during attachment, is adapted to yield or flex, the wings or members of the plate being provided with nails which are sufficiently strong and rigid to penetrate the sole without bending. As the nails project toward the end edges of said wings, they form outwardly-directed acute angles therewith, and will, in consequence, enter the sole in oppositely-inclined directions when the plate is straightened out or flattened, thereby insuring a perfectly reliable attachment of the plate to the sole.

An embodiment of the invention is illustrated in the accompanying drawing, whereof:

Figure 1 is a plan view; Fig. 2 is a side elevation, showing the manner in which the protector is initially positioned on the shoe sole; Fig. 3 is a side elevation, partly in section, showing the protector fastened to the sole; and Fig. 4 is a diagram indicating the action of the protector during the fastening operation.

Referring more particularly to said drawing, *a* indicates the gable-shaped plate, *b* the two wings or members thereof, and *c* the outwardly-directed nails with which said wings are provided.

d indicates the sole, and *e* a hole therein, caused by wear.

As shown in Fig. 2, the plate *a* is placed upon the sole, with the sharpened nails directed downwardly. Then, when the ridge line of the plate is struck, the said plate will straighten or flatten out, and the nails *c* will be driven into the sole in oppositely-inclined directions, thus preventing bending of the nails due to the resistance of the leather. As shown in Figs. 1 and 3, the plate *a* may be attached to the sole directly above the hole *e*.

During the attachment of the protector the points *f*, *g* and *h*, (Fig. 4), will move in the directions of their respective arrows, and to facilitate the attachment, said nails may be curved in conformity with their paths of movement.

I claim:

A shoe-sole protector consisting of a gable-shaped plate adapted to flatten out when struck upon its ridge line, the wings of said plate being provided upon their under faces with nails which project outwardly at acute angles to said wings toward the end edges thereof, substantially as described.

In witness whereof I have set my hand in the presence of two witnesses.

THEODOR JOHANN CAVIER.
